UNITED STATES PATENT OFFICE.

ABRAHAM LINCOLN MOLER, OF MONTREAL, QUEBEC, CANADA, ASSIGNOR OF TWO-FIFTHS TO IRVIN GRIFFITH CLAYTON AND TWO-FIFTHS TO MARTIN ALLEN BARBER, BOTH OF MONTREAL, QUEBEC, CANADA.

AUTOMATIC TRAIN-PIPE COUPLING.

1,161,403.

Specification of Letters Patent. Patented Nov. 23, 1915.

Application filed May 8, 1915. Serial No. 26,893.

To all whom it may concern:

Be it known that I, ABRAHAM LINCOLN MOLER, a citizen of the United States, and resident of the city of Montreal, Province 5 of Quebec, Canada, have invented certain new and useful Improvements in Automatic Train-Pipe Couplings, and do hereby declare that the following is a full, clear, and exact description of the same.

10 This invention relates to devices for the automatic coupling of the signal, brake and steam pipes of railway cars and has for an object to provide a new and improved connection between the shank of the coupler head and the supporting bracket.

15 The above with further objects and advantages will be hereinafter more fully described and particularly pointed out in the appended claims.

20 For full comprehension, however of my invention reference should be had to the accompanying drawings forming a part of this specification in which similar reference characters indicate the same parts and wherein:

25 Figure 1 is a side elevation of my improved coupler; Fig. 2 is a horizontal section on line 2—2 Fig. 1; Fig. 3 is a horizontal section illustrating a pair of couplers engaged, the section being indicated by line 3—3 Fig. 1; Fig. 4 is a detail section on line 4—4 Fig. 1; and Fig. 5 is a detail section on line 5—5 Fig. 2. Figs. 6 and 7 are detail sections on line 6—6 and 7—7, respectively, 35 Fig. 2.

30 Referring now to these drawings, 2 indicates a portion of a car and 3 the draw-bar of a draft rigging to which I have illustrated and will now describe my improved 40 train pipe coupler as being adjustably attached although same may be supported in any suitable manner from the draw-bar or the car.

45 A support member 4 is suspended from the draw-bar and is slotted at 5 in the longitudinal line of the car, the support having at either side thereof the upwardly extending arms 6 of a coupler supporting bracket 7. The bracket arms carry bolts 8 which pass through the slot 5 and uphold the bracket, being tightened by nuts 9 and when it is desired to adjust the position of the coupler longitudinally of the car the nuts are loosened and the bracket moved in

the desired direction with the bolts moving 55 in the slot. This adjustable connection, in itself does not form part of the present invention.

The bracket 7 extends rearwardly and downwardly and has an opening 10 there-in at its lower end, forwardly from which, or outwardly with respect to the car, extend vertical side walls 11 connected at the top by the rearwardly extending portion 7^a of the bracket, the inner surfaces of the walls 60 being each inclined as at 12 from front and rear ends inwardly in opposite directions longitudinally of the car to form a vertical ridge 13 for a purpose to be presently explained. Each of the walls 11 is provided 65 with a horizontal slot 14 extending inwardly from the outer edge of the wall and in the same horizontal plane as the opening 10, the longitudinal center line of the slots 70 preferably being level with the horizontal center line of such opening and the inner 75 end of the slots being rounded about a central point preferably in vertical line with the ridge 13 which latter is formed both above and below the slots.

80 The inner end of a shank 15 of a coupler head is loosely passed inwardly through the opening 10 and is secured in position by a sleeve-nut 16 screwed upon such inner end and bearing against the rear face of the 85 bracket, the shank 15 also passing through a spring seat 17 located in front of the bracket and having a centrally located, rearwardly extending hollow boss or sleeve 18 and rearwardly extending side arms 19 90 spaced outwardly from the boss, the latter surrounding the shank being located between the side walls 11, adapted to bear against ridges 13 and the arms 19 being located at opposite sides of the bracket 7 and 95 outside the walls 11, the shank and the openings in the spring seat, sleeve and bracket being preferably of angular form and the opening 10 in the bracket flared rearwardly at 10^a. Transversely disposed pins 20 are carried between the outer ends of the arms 19 and the boss 18, such pins being located in and adapted to bear against the inner rounded ends of slots 14 and in this instance being in the form of circular 105 and preferably hollow portions extending between the boss and arms.

The shank is preferably cast in one with

the head 22 of the coupler and the latter has an abutment face 23 surrounding the shank and between this abutment face and the spring seat a coiled spring 24 encircling the shank bears, the abutment face being provided with a centering boss 25 for the spring and for this purpose the spring seat has an outwardly extending boss 26 from which radiate webs 27.

- 10 Near the upper end of the bracket and upon the upper side of the coupler head, eyes 28 are formed and the opposite ends of a chain 29 or other flexible length are attached to these eyes to uphold the coupler head under normal and abnormal conditions. If desired a spring 30 may be set in said chain.

The coupler head is formed with train pipe apertures to which the train hose pipes 20 are connected and as is well understood when the coupler heads of two cars are brought together the spring 24 of each is compressed, the tendency of the springs to expand holding the coupler heads tightly 25 together and maintaining the apertures in communication. In a coupling constructed according to the above description, the shank, under the rearward movement of the coupler bar, slides rearwardly through 30 the bracket and spring seat and as will be apparent from Fig. 3 such coupler is permitted to move either sidewise or up and down. The vertical movement is permitted by the pins 20 which provide a horizontal 35 pivotal connection between the coupler and its bracket while the sidewise movement is permitted by the loose connection between the spring seat and the bracket and the vertical pivotal connection provided between 40 these parts by the engagement of the boss 18 with the vertical ridges 13.

The rearwardly flared opening 10 in the bracket accommodates the swinging of the inner end of the shank during both movements while the slots 14 accommodate the necessary horizontal movement of the pins 20 during the sidewise movement and it will be seen that the spring seat, owing particularly to the long bearing provided by sleeve 50 18, will follow the shank in all swinging movements thereof and thus maintain a perpendicular bearing abutment for the spring and avoid exposure of the latter to torsional strain.

55 The illustrated coupler head is of the type having a frame 31 provided with the train pipe apertures 32, 33 and 34 respectively communicating with the train pipes 35, 36 and 37, the frame being formed at one side 60 with an outwardly projecting inclined guide 38 and presenting an opening 39 at the other side adapted to receive the inclined guide of an engaging coupler head. The inner surface of the guide or that surface 65 adjacent the opening is recessed at 40 to

enable the train pipe aperture 34 to be positioned substantially in the center of the frame between the opening and guide and in axial alignment with shank 19, the latter being axially hollowed out at 41 adjacent 70 the frame and formed with a side opening 42 the side opening and central aperture communicating with each other through said shank. A laterally extending nipple 43 surrounds opening 42 for the attachment of 75 one of the train hose pipes and while a coupler head as described generally above does not form part of this invention the disposition of the side opening 42 and nipple 43 does form part of my invention. 80

The side opening 42 is disposed at the same side of the shank as is the inclined guide 38 and is also disposed at the same side of the vertical center line of the central opening 34 as is such guide and it will 85 therefore be seen that the nipple surrounding such opening and providing the rear opening of the conduit leading from its front opening, the central aperture, does not project into the line of the opening 39 nor 90 into the line of travel of the inclined projection entering such opening. In this way damage by said entering projection to the nipple or the pipe connected thereto is avoided without the necessity of setting the 95 rear opening of the conduit or the nipple so far back from the coupler head to avoid contact with the entering projection as to necessitate extreme bending of the train pipe to connect it to the nipple and the disadvantages resulting from such bending. 100

What I claim is as follows:

1. In an automatic train pipe coupler, a coupler head, a bracket for supporting the coupler head and having a slot therein, 105 a spring seat, a spring bearing between the seat and head and a projection extending from said spring seat into the slot.

2. In an automatic train pipe coupler, a coupler head, a bracket for supporting the coupler head and having a slot therein, a unitary spring seat, a spring bearing between the seat and head and a projection extending from said unitary spring seat into the slot. 110

3. In an automatic train pipe coupler, a coupler head, a bracket for supporting the coupler head and having an open slot therein, 115 a spring seat, a spring bearing between the seat and head, and a projection extending from said spring seat into the open slot.

4. In an automatic train pipe coupler, a bracket having an opening therein, walls upon the bracket, the inner surfaces of such walls presenting ridges thereon, a coupler head, a shank extending from the coupler head through said opening, a sleeve upon the shank, located between said walls and adapted to engage said ridges and a spring bearing between the sleeve and the coupler head. 120 125 130

5. In an automatic train pipe coupler, a bracket having an opening therein, side walls extending forwardly from said opening and having slots therein extending inwardly from their front ends, the interior surfaces of such walls being inwardly inclined in opposite directions from front and rear to form ridges, a coupler head at the front of the bracket, a shank extending from the coupler head rearwardly through said opening, a nut upon the rear end of the shank and adapted to bear against the rear surface of the bracket, a spring-seat surrounding the shank between the bracket and coupler head, a sleeve extending from the spring seat, located between the side walls and adapted to engage said ridges, arms extending from the spring seat and located at the outside of the side walls, pins carried by the arms and the sleeve and located in said slots and a spring bearing between the spring-seat and the coupler head. 70
- 10 6. In an automatic train pipe coupler, a bracket having an opening therein, side walls extending forwardly from said opening and having slots therein extending inwardly from their front ends and having inner rounded ends, the interior surfaces of such walls being inwardly inclined in opposite directions from front and rear to form ridges, a coupler head at the front of the bracket, a shank extending from the coupler head rearwardly through said opening, a nut upon the rear end of the shank and adapted to bear against the rear surface of the bracket, a spring-seat surrounding the shank between the bracket and coupler head, a sleeve extending from the spring seat, located between the side walls and adapted to engage said ridges, arms extending from the spring seat and located at the outside of the side walls, pins carried by the arms and the sleeve and located in said slots and a spring bearing between the spring-seat and the coupler head. 80
- 15 7. In an automatic train pipe coupler, a bracket having an opening therein, side walls extending forwardly from said opening and having slots therein extending inwardly from their front ends, the interior surfaces of such walls being inwardly inclined in opposite directions from front and rear to form ridges, a coupler head at the front of the bracket, a shank extending from the coupler head rearwardly through said opening, a nut upon the rear end of the shank and adapted to bear against the rear surface of the bracket, an extensible length extending between the upper portion of the bracket and the upper side of the coupler head, a spring-seat surrounding the shank between the bracket and coupler head, a sleeve extending from the spring seat, located between the side walls and adapted to engage said ridges, arms extending from the spring seat and located at the outside of the side walls, pins carried by the arms and the sleeve and located in said slots and a spring bearing between the spring-seat and the coupler head. 85
- 20 8. In an automatic train pipe coupler, a bracket having an opening therein, side walls extending forwardly from said opening and having slots therein extending inwardly from their front ends, the interior surfaces of such walls being inwardly inclined in opposite directions from front and rear to form ridges, a coupler head at the front of the bracket, a shank extending from the coupler head rearwardly through said opening, a nut upon the rear end of the shank and adapted to bear against the rear surface of the bracket, an extensible length extending between the upper portion of the bracket and the upper side of the coupler head, a spring-seat surrounding the shank between the bracket and coupler head, a sleeve extending from the spring seat, located between the side walls and adapted to engage said ridges, arms extending from the spring seat and located at the outside of the side walls, pins carried by the arms and the sleeve and located in said slots and a spring bearing between the spring-seat and the coupler head. 90
- 25 9. In an automatic train pipe coupler, a coupler head consisting of a frame having a projecting inclined guide at one side thereof and an opening at the other side, such frame being provided with a train pipe aperture located centrally of the frame and between the projecting guide and opening, the guide being recessed about said aperture, which latter communicates with a conduit extending rearwardly therefrom to a point out of line with the opening in the frame. 95
- 30 10. In an automatic train pipe coupler, a coupler head consisting of a frame having a projecting inclined guide at one side thereof and an opening at the other side, such frame being provided with a train pipe aperture located centrally of the frame and between the projecting guide and opening, the guide being recessed about said aperture, a shank extending rearwardly from the frame and in the axial line of said train pipe aperture, said shank being located between the projecting guide and the opening presented by the frame, being hollowed out to communicate with the aperture and having an opening leading from the interior of the shank and a nipple surrounding said opening of the shank and disposed toward the same side of the shank as that upon which the inclined guide is arranged. 100
- 35 11. In an automatic train pipe coupler, a coupler head consisting of a frame and a shank extending rearwardly from the frame and being axially hollowed out adjacent the frame, said frame presenting a forwardly 105
- 40 12. In an automatic train pipe coupler, a coupler head consisting of a frame and a shank extending rearwardly from the frame and being axially hollowed out adjacent the frame, said frame presenting a forwardly 110
- 45 13. In an automatic train pipe coupler, a coupler head consisting of a frame and a shank extending rearwardly from the frame and being axially hollowed out adjacent the frame, said frame presenting a forwardly 115
- 50 14. In an automatic train pipe coupler, a coupler head consisting of a frame and a shank extending rearwardly from the frame and being axially hollowed out adjacent the frame, said frame presenting a forwardly 120
- 55 15. In an automatic train pipe coupler, a coupler head consisting of a frame and a shank extending rearwardly from the frame and being axially hollowed out adjacent the frame, said frame presenting a forwardly 125
- 60 16. In an automatic train pipe coupler, a coupler head consisting of a frame and a shank extending rearwardly from the frame and being axially hollowed out adjacent the frame, said frame presenting a forwardly 130
- 65 17. In an automatic train pipe coupler, a coupler head consisting of a frame and a shank extending rearwardly from the frame and being axially hollowed out adjacent the frame, said frame presenting a forwardly 135

extending inclined guide at one side, an opening at the other side and a train pipe aperture located between the guide and opening and in longitudinal alinement with the shank, with the interior of which latter it communicates, said hollowed out shank being provided with an opening leading from the interior thereof and a nipple surrounding said opening and disposed at the same side of the center of the train pipe

5 aperture as that upon which the inclined projecting guide is located.

In testimony whereof, I have signed my name to this specification, in the presence of two subscribing witnesses.

ABRAHAM LINCOLN MOLER.
